(57) CLAIM

The ornamental design of a splitback pillow top sofa with wing-arms, as shown and described.

DESCRIPTION

FIG. 1 is a front perspective view of a new design of a splitback pillow top sofa with wing-arms, wherein the sofa is in a first position;

FIG. 2 is a front perspective view of the splitback pillow top sofa with wing-arms, wherein the sofa is in a second position;

FIG. 3 is a front perspective view of the splitback pillow top sofa with wing-arms, wherein the sofa is in a third position;

FIG. 4 is a front perspective view of the splitback pillow top sofa with wing-arms, wherein the sofa is in a fourth position;

FIG. 5 is a front perspective view of the splitback pillow top sofa with wing-arms, wherein the sofa is in a fifth position;

FIG. 6 is a front view of the splitback pillow top sofa with wing-arms, wherein the sofa is in the first position;

FIG. 7 is a right side view of the splitback pillow top sofa with wing-arms, wherein the sofa is in the first position;

FIG. 8 is a left side view of the splitback pillow top sofa with wing-arms, wherein the sofa is in the first position;

FIG. 9 is a top view of the splitback pillow top sofa with wing-arms, wherein the sofa is in the first position;

FIG. 10 is a bottom view of the splitback pillow top sofa with wing-arms, wherein the sofa is in the third position; and,

FIG. 11 is a back perspective view of the splitback pillow top sofa with wing-arms, wherein the sofa is in the first position.
